UNITED STATES PATENT OFFICE

96,195

DESIGN FOR A STREAMLINE SLED OR SIMILAR ARTICLE

Charles W. Morris, Niles, Mich.

Application November 15, 1934, Serial No. 54,036

Term of patent 14 years

To all whom it may concern:

Be it known that I, Charles W. Morris, a citizen of the United States, residing at Niles, in the county of Berrien in the State of Michigan, have invented a new, original, and ornamental Design for a Streamline Sled or Similar Article, of which the following is a specification, reference being had to the accompanying drawing, forming a part thereof, in which,—

Fig. 1 is a plan view of a sled showing my design; and

Fig. 2 is a side elevational view of the same.

I claim:

The ornamental design for a streamline sled or similar article, substantially as shown.

CHARLES W. MORRIS.
